UNITED STATES PATENT OFFICE

EDWARD W. BULLARD, OF SAN FRANCISCO, CALIFORNIA, ASSIGNOR TO PACIFIC SAFETY EQUIPMENT COMPANY, OF SAN FRANCISCO, CALIFORNIA, A CORPORATION OF CALIFORNIA

SAFETY HAT

Application filed August 14, 1928. Serial No. 299,542.

My invention relates to hats, and especially to those worn by persons working in localities where there is danger of being struck by falling objects and where the wearer is subjected to conditions of moisture.

An object of my invention is the provision of a hat possessed of a sufficient degree of rigidity to protect the wearer from injury by falling objects, and still light enough to be worn without discomfort.

Another object of my invention is the provision of water-proofing means in a hat of the character described.

Another object of my invention is the provision of ventilating means in a hat of the character described.

My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawings:

Figure 1 is a vertical sectional view of the hat of my invention, taken in a longitudinal median plane.

Figure 2 is a sectional view showing in detail the assembly of the water-proof covering and hat crown.

Figure 3 is a rear view of the hat. Portions of the structure are omitted to show the construction more clearly.

Figure 4 is a perspective view illustrating the resilient ventilator spacer; and Figure 5 is a front view thereof.

Figure 6 is a plan view, on a reduced scale, of the blank from which the crown of the hat is formed.

Safety hats constructed of hard compacted inert sheet fiber and having parts stitched together, are generally coated with an asphaltic or other seal coating to make them water-proof. The coating adheres to the fibrous sheet with difficulty, and after a while the coating chips off leaving portions

of the crown unprotected. If these unprotected portions are subjected to moisture, the fiber becomes soft thereby weakening the hat. The stitched portions of the hat also afford very little protection from moisture, causing the same thing to happen. The hat of my invention is primarily designed to overcome this defect, and at the same time I provide proper ventilation for the head of the wearer.

In terms of broad inclusion, the hat of my invention comprises a hat crown constructed of light, nonmetallic material strong enough to protect the wearer from injury by thrown or falling objects, such as rocks, bricks, tools, hot rivets and the like. Over the crown is placed a water-proof covering such as oil cloth or cloth treated with a nitro-cellulose solution, and this covering is positioned to protect the entire crown and also the junction of the brim and crown. I prefer to use a crown section provided with notched edges to facilitate shaping of the crown and a ring for holding the notches partially closed to provide openings in the crown. For ventilating the hat, I provide apertures in the covering in a position adjacent the crown openings and means for spacing the cover from the openings.

In greater detail, the hat crown of my invention is constructed from relatively thin sheet material which is light enough not to make the hat cumbersome and uncomfortable, and still has sufficient rigidity to protect the wearer from injury from falling objects. For this purpose I prefer to use hard compacted sheet fiber, substantially $\frac{3}{2}$ of an inch in thickness, because it is tough, chemically inert, and a non-conductor of both heat and electricity.

As illustrated in Figure 6, the shape of the crown section before it is steamed and pressed into shape is substantially an ovoid blank 3 punched or otherwise cut from a sheet of the hard fiber. The blank is provided with notches 4 and 6 at the intersection of the periphery with the major axis 7 and minor axis 8 respectively, to facilitate forming the blank to the desired shape.

After being steamed for about a quarter

of an hour, the fiber becomes sufficiently pliable to be readily pressed into the form of a crown, with the notches substantially closed. A retaining ring 9 preferably of hard compacted fibrous material and larger than the head size of the wearer, is then secured to the edge of the crown to hold the notches substantially closed. While these parts may be secured together in any desired way, it is preferred to sew them together with a row of stitches 10. The crown thus formed is possessed of the inherent advantages of dome construction, with the result that although it weighs but a few ounces, it is strong enough to support fully 250 pounds without being deformed. It is to be noted that although the ring holds the notches substantially closed, they are not entirely closed; hence openings or apertures are provided in the crown.

A water-proof covering 11 of a single sheet of material is cut and formed to the shape of the crown. Preferably the material is canvas or drill cloth which has been treated with oil, paint or a nitro-cellulose solution to make it water-proof. This cloth is of substantially the same character as that used for "slickers". Before the covering 11 is placed over the crown, a ring 12 preferably of soft material such as "fabricoid", cloth or other soft fibrous material and of a size adapted to fit over the ring 9, is secured to the covering a short distance from its periphery by means of stitches 13, and the lower edge of the cover is turned back over the stitches as shown by the dotted lines in Figure 2. When the cover is placed over the crown it fits snugly thereon and the rings 12 and 9 are conveniently positioned.

After the cover is fitted on the crown, a supporting lining 14, preferably of cloth and having a lower edge 16 of leather to provide a sweat band, is secured to the outer surface of the crown by means of stitches 17 passing thru rings 9 and 12. The upper edge of the lining is hemmed, and a draw string 18 in the hem provides means for adjusting the lining, so as to determine the position of the hat on the head of the wearer. A brim or visor 19 preferably of the same material as the crown, is next secured to the crown by means of stitches 21 passing thru rings 9 and 12. The upturned edge 55 of the water-proof covering is then turned down to lap over the upper edge of the brim and thus cover all the stitches.

From the preceding description it is seen, that although the covering is not secured directly to the crown sheet 3, it is permanently fixed to the hat. Also it is to be noted that the cover protects the stitches and laps over the brim to provide a shingle effect; thereby completely water-proofing the hat. Preferably the brim is covered on

both surfaces with a water-proof coating such as a paint with an asphalt base.

As previously set forth, the partially closed notches in the crown provide openings; and advantage is taken of this to ventilate the hat without destroying its water-proof characteristic. Slots or apertures 22 are formed in the covering 11 preferably adjacent two or more of the openings or notches, and the slots are sewed at the corners to prevent tearing of the cover. Triangularly shaped resilient ventilator spacers 23 preferably of inert fibrous material are arcuately formed by steaming, so that they can be sprung inwardly to pass thru the slots, and when released the covering is held away from the openings to provide a space between the openings and cover. Each of the spacers 23 is provided with notches 24 adapted to engage the corners of the slots 22, so as to hold the spacers in position. When the spacers are inserted thru the slots and between the cover and crown, their lower edges overlap the portion of the cover below each slot; thereby preventing penetration of water thru the slots, and at the same time air can circulate thru the slots and openings. To insure the spacing of the cover from the crown openings so that air can properly pass therethru, the spacer 23 may be provided with a band of flexible material 26, such as metal, secured at the edges of the spacer to prevent flattening thereof when placed in any of the apertures 22.

While I have described my invention as embodied in the form of a hat, I am aware that it may also be applied to a cap, helmet, or any other form of headgear.

I claim:

1. A safety headgear comprising a crown formed from a single sheet of hard compacted fibrous material having a plurality of notches in the periphery thereof to facilitate shaping the crown, a retaining ring secured adjacent the edge of the crown to hold the notches substantially closed, a water-proof cover over the crown, and means securing the cover to the ring.

2. A safety headgear comprising a crown formed from a single sheet of hard compacted fibrous material having a plurality of notches in the periphery thereof to facilitate shaping the crown, a retaining ring secured adjacent the edge of the crown to hold the notches substantially closed, a brim secured to the ring, a water-proof cover over the crown and overlapping the brim, and means securing the cover to the ring.

3. A safety headgear comprising a crown formed from a single sheet of hard compacted fibrous material having a plurality of notches in the periphery thereof to facilitate shaping the crown, a retaining ring secured adjacent the edge of the crown to hold

the notches substantially closed, a water-proof cover over the crown, a ring secured to the cover and adjacent the retaining ring, and a brim secured to the rings, the lower edge of the cover overlapping the brim.

5. A safety headgear comprising a crown of hard compacted fibrous material, a ring secured adjacent the edge of the crown, a water-proof cover over the crown, a ring secured to the cover and adjacent the first ring, and a brim secured to the rings, the lower edge of the cover overlapping the brim.

10. 6. In a headgear, a crown having an opening, a cover on the crown and over the opening, said cover having an aperture adjacent the opening, and means engaging the cover and projecting through the aperture for spacing the cover from the crown opening.

20. 7. In a headgear, a crown having an opening, a cover on the crown and over the opening, said cover having an aperture adjacent the opening, and a spacer in the aperture and interposed between the crown and cover.

25. 8. A safety headgear comprising a crown of hard compacted fibrous material having an opening, a water-proof cover on the crown and over the opening, said cover having an aperture adjacent the opening, and a spacer in the aperture and interposed between the crown and cover.

30. 9. A safety headgear comprising a crown formed from a single sheet of hard compacted fibrous material having a plurality of notches in the periphery thereof to facilitate shaping the crown, means for holding the notches substantially closed, a water-proof cover on the crown and over the notches, said cover having an aperture adjacent a notch, and means adjacent the aperture for spacing the cover from the notch.

35. 10. A safety headgear comprising a crown formed from a single sheet of hard compacted fibrous material having a plurality of notches in the periphery thereof to facilitate shaping the crown, means for holding the notches substantially closed, a water-proof cover on the crown and over the notches, said cover having an aperture adjacent a notch, and a spacer in the aperture and interposed between the crown and cover.

40. 11. A safety headgear comprising a crown of hard compacted fibrous material, a retaining ring stitched to the crown adjacent the lower edge thereof, a waterproof cover over the crown, a ring stitched to the cover adjacent the retaining ring, and a brim stitched to the rings, the lower edge of the cover overlapping the brim and the stitching securing the rings and brim to the crown.

45. 12. In a headgear, a crown of sheet material and having an opening, a cover completely over the crown and opening, said cover having an aperture adjacent the open-

ing, and means for spacing the cover from the crown opening.

In testimony whereof, I have hereunto set my hand.
